United States Patent Office

Des. 230,067

Patented Jan. 22, 1974

230,067

COMBINED CANDLE AND HOLDER THEREFOR

Roy Van Horn, Jr., Houston, Tex., assignor to Van Horn Hayward, Houston, Tex.

Filed Oct. 27, 1971, Ser. No. 193,229

Term of patent 14 years

Int. Cl. D26—01

U.S. CL. D48—2

FIG. 2

4 →

FIG. 4

FIG. 3

FIG. 1 is a side view of a combined candle and holder therefor showing my new design;

FIG. 2 is a top plan view thereof;

FIG. 3 is a bottom plan view thereof; and,

FIG. 4 is a cross sectional view taken on line 4—4 of FIG. 1.

I claim:

The ornamental design for a combined candle and holder therefor, as shown.
